DISPENSER FOR ROLLED PAPER

Anton P. Maier, 3410 W. Layton Ave., Greenfield, Wis.

Filed Feb. 18, 1955, Ser. No. 489,199

2 Claims. (Cl. 242—55.2)

This invention relates generally to a dispenser for rolled paper and more particularly to an improved dispenser for dispensing rolled paper in sheets of a length established by perforations across the width of the paper at equal intervals along its length.

Paper towels, toilet paper, and similar paper specialties are often furnished in rolls with the roll being divided into sheets of a specific length by perforations or other means for weakening the tensile strength of the paper across its width at particular intervals along its length. A variety of appliances are available for holding such paper rolls, but they are either of relatively complicated construction or are inconvenient to operate in separating the individual sheets forming the continuous roll of paper. In those devices which do not include a complex mechanism for holding the roll of paper while a sheet is being torn from the roll, it is necessary to hold the roll with one hand while tearing the sheet off with the other hand. If the roll is not held either by hand or by a mechanical device, and the sheet is pulled sharply to tear it off the roll, the instantaneous force applied causes the roll to overrun on its spindle after the sheet has been torn away, and the paper unrolls from the roll to hang downwardly from it, leaving it unsightly, and renders it increasingly inconvenient for subsequent use.

It is therefore a general object of the present invention to provide an improved dispenser for rolled paper especially adapted to remove the paper in relatively short lengths from the continuous roll.

Another object of the present invention is to provide an improved dispenser for rolled paper with simple restricting means for preventing overrun of the roll from the force applied to tear a sheet off of the roll.

A still further object is to provide a dispenser for rolled paper of simple and inexpensive but sturdy construction which is convenient and efficient in operation.

According to this invention the improved dispenser for rolled paper comprises a bracket having an extending arm for supporting the roll of paper. A pair of rings are secured to the arm in spaced relationship and are fabricated of rubber or other similar material having a relatively high frictional resistance to sliding movement. The rings receive the core of the roll so that the roll is carried by the two rings on the arm. Sufficient clearance is provided between the outer diameter of the rings and the inner diameter of the core of the roll of paper to permit the roll to revolve about the two rings when a light steady tangential force is applied to the roll by drawing easily upon the exposed end of the roll of paper. However, when a sharp tangential force is applied to the roll as will result from tearing a sheet off of the roll, the frictional resistance of the rings functions to restrict the rotation of the roll of paper, permitting the sheet to be torn off of the roll while at the same time preventing overrun of the roll after the sheet has been torn away.

The foregoing and other objects of this invention, which will become more fully apparent from the follow-

2

ing detailed description of an embodiment thereof, may be achieved by the apparatus herein described by way of example, in connection with the illustrations of its structural components in the accompanying drawings, in which:

Figure 1 is a view in front elevation depicting a dispenser embodying the features of the present invention, with one of the rings being broken away to illustrate its mounting;

10 Figure 2 is a plan view of the dispenser shown in Figure 1;

Figure 3 is a view in side elevation of the dispenser depicted in Figure 1, with a portion of one of the rings broken away to illustrate its mounting; and

15 Figure 4 is a detail perspective view of one of the two rings which support the roll of paper.

Reference is now made more particularly to the drawings showing a dispenser for rolled paper embodying the principles of the present invention and comprising an

20 L shaped bracket 5 for mounting the dispenser on a wall or other structure. The L shaped bracket 5 includes a short leg 6 and a long leg 7 with the latter being in the shape of a truncated triangle as seen in Figure 3, with its base joining the short leg 6 and its line of truncation 25 constituting the juncture with an arm 8 disposed substantially perpendicular to the long leg 7. Thus, the long leg 7 serves to support the arm 8 in spaced relation to the wall to provide clearance for a roll of paper carried by it. The short leg 6 is provided with a pair of holes 30 for receiving screws 9 which are screwed into the wall to secure the dispenser thereto.

It will be noted that the drawings illustrate the short leg 6, the long leg 7, and the arm 8 formed integrally from a single sheet of metal bent at the junctures of the 35 three members as a preferred embodiment. Such construction is very inexpensive but sturdy, it being only necessary to stamp the sheet of metal to the required configuration and then bend the stamping to form the three members described.

40 The arm 8 is provided with two pairs of notches 14 with the notches of each pair being oppositely disposed

across the width of the arm 8, and the two pairs of notches 14 being disposed in spaced relationship along the length of the arm 8. Each pair of notches is adapted to receive a ring or annular member 15 fabricated of 45 rubber or other similar material, it having been found that a material having a relatively high frictional resistance to sliding movement with the core of the roll of paper is preferable for producing the retarding effect on the rotation of the roll of paper, and a flexible material 50 will facilitate the assembly of the rings on the arm 8 as will be presently seen.

A portion of the rings 15 are disposed within the notches 14 to prevent their lateral movement along the arm 8, but their peripheries extend beyond the longitudinal edges of the arm 8 for the purpose of receiving the roll of paper. In order to produce the desired effect it is preferred that the rings 15 do not rotate relative to the arm 8, and to this end diametrically opposite slots or notches 16 are formed in the rings 15 in their inner diameter as seen in Figures 3 and 4. The dimension of the arm 8 between the bottoms of each pair of notches 14 is greater than the inner diameter of the rings 15 so that in order to place the rings in the notches 14 it is necessary to insert the edges of the bottom of the notches 14 60 within the notches 16 of the rings 15.

With this arrangement the rings 15 are securely fixed on the arm 8, the notches 14 preventing their lateral movement on the arm 8, and the notches 16 preventing their rotational movement relative to the arm 8. If the 70 rings 15 are fabricated of a flexible material, such as rubber, it is a simple matter to flatten their rotundity and

distend their inner diameter in the plane of the arm 8 to clear the notches 14 so that they can be slid off of the arm 8.

Paper of the type for which the dispenser is intended is usually rolled upon a cardboard core, and the outer diameter of the rings 15 is smaller than the inner diameter of the core to provide enough clearance so that the fit between the rings 15 and the core of the roll of paper will not interfere with the rotation of the roll on the rings. With such arrangement, the roll of paper will rotate freely when a light tangential force is applied to its outer diameter by an easy steady pull on the extending end of the paper, but its rotation will be retarded by the frictional resistance of the rings 15 when a sharp force is applied as will occur when a sheet of paper is torn off of the end of the roll.

The roll of paper is indicated diagrammatically in the drawings by broken lines and is identified by the reference numeral 20. It is shown assembled to the dispenser with its core embracing the rings 15 to be supported thereby for the limited rotational movement as described.

In order to retain the roll of paper 20 on the arm 8, the latter is provided with a retainer member 21 at its extending end secured to the arm 8 for pivotal movement relative thereto by a rivet 22 or other suitable securing means. A spring 23 is interposed under one head of the rivet 22 to maintain the retainer 21 in frictional contact with the end of the arm 8 for the purpose of maintaining the retainer 21 in a desired pivotal position. To retain the roll of paper 20 on the arm 8 it is only necessary to position the retainer 21 transversely of the arm 8 as illustrated in solid lines in Figure 1 so that it will interfere with lateral movement of the roll 20 off of the arm 8. When it is desired to place a roll of paper on the arm 8, or remove it or its core therefrom, the retainer 21 may be simply pivoted into alignment with the arm 8 as illustrated in broken lines in Figure 1, and the core of the roll of paper may be readily passed over it in either direction.

Such construction, in which a pair of rings is provided for supporting the roll of paper in lieu of the customary cylindrical spindle, is relatively inexpensive. These rings are additionally advantageous in that they may have a surface presenting frictional resistance to sliding movement with the core of the roll of paper, so that when a sharp force tending to rotate the roll of paper is applied, the rings will retard the rotation of the roll and prevent it from overrunning when a sheet of paper is torn off of it. On the other hand, the frictional resistance of the rings will not interfere with the rotation of the roll when a light force is applied to unroll a portion of the paper from the roll. The paper may therefore be readily manipulated with one hand by simply pulling lightly on the extending end of the roll of paper to unroll the desired length of paper from the roll, and then applying a sharp force to tear the length from the roll without the roll overrunning. The tearing operation is facilitated by the presence of perforations or other paper weakening means across the width of the paper at intervals to establish the individual sheets forming the continuous roll, as the separation of the paper will occur in a straight line along such perforations.

From the foregoing detailed description of the construction and operation of a practical embodiment of the dispenser for rolled paper provided by the present invention, it will be apparent that the apparatus is of simple construction especially adapted for dispensing sheets of paper from a continuous roll and preventing the roll from overrunning due to the force applied in tearing a sheet off of the roll.

Although the illustrative embodiment of the invention has been described in considerable detail for the purpose of setting forth an operative and practical exemplifying structure, it is to be understood that the structure shown and described is intended to be illustrative only, and that various characteristics of the invention may be incorporated in other structural forms without departing from the spirit and scope of the invention as defined in the subjoined claims.

10 The principles of the invention having now been fully explained in connection with the foregoing description of embodying structure, I hereby claim as my invention:

15 1. In a dispenser for rolled paper having an axial cylindrical opening, a bracket adapted to be mounted on a supporting structure, an arm carried by said bracket in spaced relationship to the supporting structure, said arm having a plurality of notches spaced along its length, a plurality of flexible rubber rings having a smooth unbroken peripheral surface and an outer diameter smaller than the diameter of said cylindrical opening and carried by said arm in said notches in axial alignment for insertion into said cylindrical opening to support the roll on their peripheries for rotation relative thereto, said rings having slots formed in their inner diameters for receiving the bottom edges of said notches, and a retainer operatively secured to said arm to prevent lateral displacement of the roll of paper off of said rings, whereby the peripheral surface of said rubber rings presents a frictional resistance to sliding movement with the paper about said cylindrical opening to retard overrunning of the roll when a sharp tangential force is applied as will occur when a sheet of paper is torn off of the roll, and the notches in said arm prevent lateral displacement of the rings on the arm while the bottom edges of the notches in the slots of said rings prevent the rings from rotating relative to the arm.

20 2. In a dispenser for rolled paper having an axial cylindrical opening, a bracket adapted to be mounted on a supporting structure, an arm carried by said bracket in spaced relationship to the supporting structure, said arm having a plurality of notches spaced along its length, a plurality of rings having a smooth unbroken peripheral surface presenting a frictional resistance to sliding movement with the paper forming said cylindrical opening, said rings having an outer diameter smaller than the diameter of said cylindrical opening and being carried by said arm in said notches in axial alignment for insertion into said cylindrical opening to support the roll on their peripheries for rotation relative thereto, said rings having diametrically opposite slots formed in their inner diameters for receiving the bottom edges of said notches, and a retainer operatively secured to said arm to retain the roll of paper on said rings, whereby the roll of paper may be rotated on said rings by pulling steadily upon the outer end of the roll of paper, but the peripheral surface of said rings will retard overrunning of the roll when a sharp tangential force is applied as will occur when a sheet of paper is torn off of the roll, and the notches in said arm prevent lateral displacement of the rings on the arm while the bottom edges of the notches in the slots of said rings prevent the rings from rotating relative to the arm.
